(57) **CLAIM**

The ornamental design for a display screen or portion thereof with a graphical user interface for analyzing and presenting drilling data, as shown and described.

DESCRIPTION

FIG. 1 is a front view of a display screen or portion thereof with a graphical user interface for analyzing and presenting drilling data;

FIG. 2 is a detailed view of a portion of the display screen shown in FIG. 1;

FIG. 3 is a detailed view of a portion of the display screen shown in FIG. 2;

FIG. 4 is a detailed view of a portion of the display screen shown in FIG. 1;

FIG. 5 is a detailed view of a portion of the display screen shown in FIG. 4;

FIG. 6 is a detailed view of a portion of the display screen shown in FIG. 1;

FIG. 7 is a detailed view of a portion of the display screen shown in FIG. 6;

FIG. 8 is a detailed view of a portion of the display screen shown in FIG. 1; and,

FIG. 9 is a detailed view of a portion of the display screen shown in FIG. 8.

The broken line showing of a display screen with graphical user interface is included for the purpose of showing portions of the article and forms no part of the claim.

1 Claim, 9 Drawing Sheets
